R. H. Hamilton

UNITED STATES PATENT OFFICE.

RUDOLPH SCHMIDT, OF ROSEDALE, KANSAS.

TRUSS.

Application filed March 15, 1926. Serial No. 94,769.

This invention relates to surgical trusses of that class having an encircling spring and strap and equipped with pads at the ends of the spring, one for bearing against 5 the back of the patient and the other for applying pressure at the point where the hernia requires support or retention. There have been many devices of this class patented and many marketed, but none with 10 which I am familiar, retains the hernia with a substantial uniformity of pressure comfortable in all attitudes which the patient may assume, and my special object is to produce a truss of simple, strong, durable and 15 inexpensive construction, having the front end hernia pad so yieldingly supported that excess pressure applied, through bending movements of the body, on the pad above or below its horizontal diameter, shall meet 20 with correspondingly increased resistance to the end that the hernia shall be properly supported at all times, the pressure of the pad being always of a yielding character around said horizontal center so that while 25 affording proper support, the patient shall be subjected to the least possible discomfort.

With this general object in view, the invention consists in certain novel and useful features of construction and combinations of 30 parts as hereinafter described and claimed; and in order that it may be fully understood, reference is to be had to the accompanying drawing, in which:

Figure 1 is a perspective view of a truss 35 embodying my invention.

Figure 2 is an enlarged top plan of the front pad and its connections.

Figure 3 is an inner face view of the construction shown by Figure 2.

Figure 4 is a vertical section taken on the 40 line IV—IV of Figure 3.

Referring to the drawing in detail, 1 indicates a substantially semi-circular spring for fitting around one side of the body of 45 a patient, 2 a strap to fit around the opposite side, and 3 a back pad suitably mounted at the junction of the spring and strap, the former having a suitable rubber or fabric covering 4 for cushioning purposes, as customary. The front end of the spring 1 terminates in an outwardly extending rosette 4^a, and a short angle arm 5 has at one end, a rosette 5^a pivoted to rosette 4^a at 5^b, and at the other end a rosette head 5^c adjustably 50 engaged by the corresponding head of a

short plate 6, the two heads being clamped firmly together by a pivot bolt and nut connection 7. The arrangement described permits the plate 6 to be rotatably adjusted around pivotal point 5^b, and to be adjusted 60 pivotally on the pivotal connection 7 for the purpose of applying pressure by the front pad, hereinafter described, at the most effective point on the body of any patient. It accommodates the pad to bodies of materially different contour.

A screw bolt 8 is mounted in and projects from the front end of the plate 6 and a lock nut 9 engages the bolt and front end of the plate.

A disk 10 is provided on its front or outer face with a radial tubular lug 11, and projecting from the same side of the disk in a plate perpendicular to that of the lug and at the opposite side of the axial center from the lug and equal distances from said center, is a pair of headed pins 12 for securing to the disk the front ends of the arms of a substantially V-shaped spring 13, secured at its apex coincidentally with the axis of plate 6, by the pivotal fastening devices 7, the arrangement being such that the arms of said spring shall apply uniform pressure rearwardly on the disk above and below its axis, either arm being adapted to yield outwardly in the event of encountering a pressure in excess of that normally sustained, that is to say, either arm of the spring is capable of yielding outwardly in the event it is subjected to greater pressure due to bending or twisting movements of the body.

The disk 10 is provided centrally with a hollow protuberance 14 concaved at its rear edge and engaging a semi-circular central projection 15 of a circular plate 16. The plate 16 forms the frame of the front pad, and is provided marginally with an outwardly projecting circular flange 17 beaded at its front edge. A covering 18 of soft material of any suitable character fits over the inner or rear face of the frame and around the flange 17 and its beaded edge, and a spring 19 fits within the frame and bears against the edge of the cover 18 to clamp the same firmly against the flange and bead for the purpose of dependably securing the cover in place. A light spring 20 is attached at one end to the center of the frame 16 and at the other end by a removable pin 21 to the disk 10, so as to hold the pad in yielding 100 105 110

engagement with the protuberance 14 without interfering with rocking self-adjustments of the pad relative to the disk.

The device is applied to the body in the customary manner, after making such adjustments of the parts 5 and 6 as necessary to apply the pad in a firm and comfortable manner to the body, it being understood that the contour of the latter will determine such adjustments. When the proper positions of the parts 5 and 6 have been attained, the strap 22 slidably attached to the main strap 2, is adapted to be buttoned onto the pins 12, the strap 22 having a plurality of slits or buttonholes 23 for adjustment to accommodate the girth of the wearer. It will be apparent that when the truss is applied, the pad is capable of rocking slightly relative to the disk 10, and that the disk 10 being swivelled on the bolt 8, is capable of rocking to accommodate the pad to such movements of the body as tend to effect changes in the position in the pad and disk, and spring arms 13 tend, of course, to maintain the pad firmly against the body regardless of the position of the latter.

From the above description, it will be apparent that I have produced a truss embodying the features of advantage set forth as desirable in the statement of the object of the invention, and which may be modified in minor particulars without departing from the principle of construction and mode of operation involved.

I claim:

1. In a truss, a pad and a disk having a ball and socket relation, the disk at its outer

or opposite side from the pad having a radially disposed lug and a pair of pins, the latter at opposite sides of and equal distances 40 from the radial plane of the lug and at the opposite side from the lug of a plane intersecting the first-named plane at the axial center of the disk, a suitably-supported plate, a bolt carried thereby and extending through 45 the said lug and forming a journal therefor, and a spring secured to the said plate and having diverging arms respectively attached at their free ends to said pins.

2. A truss comprising a semi-circular 50 spring, a strap, a back pad suitably connected to adjacent ends of the spring and strap, a strap slidably attached at an intermediate point of its length to the free end of the first-named strap and having a plurality of button holes in each end, an angle plate secured to the free end of the said spring, a plate pivoted to the angle plate, a bolt secured to and projecting from said plate, a disk provided at its outer side with a radial 60 lug fitting on said bolt for turning movement thereon, a pair of headed pins projecting outwardly from the disk at opposite sides of and equal distances from the radial plane of 65 said lug, a spring secured to the plate carrying the bolt and having diverging arms respectively engaging said headed pins, and a pad carried at the inner side of said disk; said sliding strap being adapted for engagement with said headed pins. 70

In witness whereof I hereunto affix my signature.

RUDOLPH SCHMIDT.
